UNITED STATES PATENT OFFICE.

DAVID MORRIS THOMSON, OF TORONTO, ONTARIO, CANADA.

SUPPORT FOR PEN-HOLDERS.

1,359,548.

Specification of Letters Patent. Patented Nov. 23, 1920.

Application filed June 1, 1920. Serial No. 385,442.

To all whom it may concern:

Be it known that I, DAVID MORRIS THOMSON, a subject of the King of Great Britain, and resident of the city of Toronto, county of York, Province of Ontario, in the Dominion of Canada, have invented certain new and useful Improvements in Supports for Pen-Holders, described in the following specification and illustrated in the accompanying drawings, that form part of the same.

The principal objects of this invention are, to avoid the soiling of the table or desk through the laying of a pen thereon, and to provide a simple form of pen rest which may be applied to ink bottles in such a way as to be always ready to hand when the ink is being used.

The principal feature of the invention consists in the novel arrangement of a supporting member within the ink bottle cap to support and hold the pen above the table or desk surface.

In the drawings, Figure 1 is a perspective view of my improved pen holder showing a pen supported therein.

Fig. 2 is a perspective view of a bottle cap showing a slightly modified construction.

Fig. 3 is a perspective detail of the holder member detached from the bottle cap.

In the ordinary use of a pen and ink, when the person lays the pen down there is great danger of marring the cover of the table or desk through the pen rolling and in order to overcome this difficulty and provide a ready means for supporting the pen

I provide within the bottle cap 1 a forked

member 2 preferably formed of a piece of spring wire having the ends extending from the underside of the cap and adjacent to the 40 extremities, the ends of the forked members are bent outwardly into a semi-looped shape 3 provided with flaring extremities 4. This forms a very handy receptacle for the pen handle which is simply pressed into place 45 between the flaring ends and is held securely from rolling.

In the form shown in Fig. 2 the supporting member 2 is formed of a single length of wire 5 having the central portion formed 50 into a semi-circular spring loop 6 adapted to fit the inner periphery of the bottle cap. The ends 6' of the loop are turned radially inward and from the center extend upwardly forming a supporting fork 7. 55

A device such as described is extremely simple and can be applied to all ink bottles.

What I claim as my invention is:—

1. In a support for a pen holder, the combination with a bottle cap, of a forked member secured within the bottle cap and adapted to receive a pen holder. 60

2. In a support for a pen holder, the combination with a bottle cap, of a spring wire loop adapted to fit within the rim thereof 65 and having inwardly turned ends forming a fork to receive and hold a pen holder.

3. In a support for a pen holder, the combination with a bottle cap, of a pair of wire fingers extending inwardly from the top of 70 the bottle cap having outwardly flaring bent ends adapted to spring apart and to grip and hold a pen holder.

DAVID MORRIS THOMSON.
